INVENTOR.
R. C. Wade,

BY

Geo. F. Kimmel, ATTORNEY.

UNITED STATES PATENT OFFICE.

ROBERT C. WADE, OF BROWNSVILLE, TEXAS.

OIL BURNER.

Application filed March 28, 1923. Serial No. 628,283.

To all whom it may concern:

Be it known that I, ROBERT C. WADE, a citizen of the United States, residing at Brownsville, in the county of Cameron and 5 State of Texas, have invented certain new and useful Improvements in Oil Burners, of which the following is a specification.

This invention relates to oil burners and is designed to use an oily fuel, which is not 10 under pressure, and air, or steam, which is under pressure, and direct it into the air stream for feeding the oil to the burner by pressure exerted on the air stream, to direct the combined streams of air or steam and 15 fuel through the nozzle of the burner.

In accordance with the invention, there is provided a nozzle entering a body or sleeve which is made of massive construction except where particular massiveness is not desired, and into the nozzle there is directed an air or steam feed with the air or steam under pressure and so arranged as to issue through the nozzle in an axial stream.

The sleeve is somewhat larger in diameter 25 than the air stream, and the fuel is directed to the sleeve through one side of the latter and into the air stream to be drawn thereby and injected through the sleeve, which latter in the larger sizes of nozzles provides 30 means for the mixing of the air and fuel before being ejected and consumed.

In combined air or steam and fuel nozzles as heretofore constructed, it is customary to utilize the streams simultaneously, both 35 streams being under pressure and the mixing taking place at the exit end.

In accordance with the present invention, the air or steam stream is the only stream under pressure, and this air stream is arranged centrally with respect to the fuel stream and issues through a nozzle into one side of which the fuel stream is directed.

In accordance with the invention, there is provided an air pipe centrally of a nozzle 45 through which the air is directed, and this air nozzle is surrounded by a heavier walled tube extending beyond the exit end of the air nozzle, while the fuel is fed to one side of the air nozzle so that the streams of fuel 50 and air join and are together ejected through the air nozzle to pass out together through another larger nozzle where the mixture of the two streams takes place.

These two streams unite and mix before 55 issuance from the mouth of the burner, and the supply of air close to the fuel is such

as to thoroughly sustain combustion, while at the same time the stream of fuel is drawn into and burns as it escapes from the air nozzle without any back pressure in the fuel 60 nozzle.

For this reason, the feed of fuel through the burner is due entirely to the pressure created by the issuance of the air drawing 65 on the supply of fuel.

The invention will be best understood from a consideration of the following detailed description taken in connection with the accompanying drawings forming part of this specification, with the understanding 70 that the invention is not confined to any strict conformity with the showing of the drawings, but may be changed and modified so long as such changes and modifications 75 mark no material departure from the salient 75 features of the invention as expressed in the appended claim.

Figure 1 is a longitudinal central section, partly in section, of the improved device.

Fig. 2 is a section on the line 2—2 of 80 Fig. 1.

Fig. 3 is a longitudinal section partly in section, of a smaller type of burner incorporating the principles of the burner illustrated in Figs. 1 and 2.

Referring to the drawings, there is shown a cylindrical main stock or body 1 having an enlarged longitudinal bore 2 at the rear end which leads into an axial smaller bore 3 opening at the forward end.

The bore 2 is interiorly threaded as at 4 and into this bore is threaded a reduced extension 6 constituting an inner nozzle, extending from a minor body portion 5 which is, as shown, of the same diameter as the body 1. The body 5 is provided with an axial bore 8 which extends into the nozzle or extension 6 and the extension has an axial bore 8^a formed therethrough of materially less diameter than the bore 8 and in alignment therewith.

The bores 2 and 3 are joined by a tapered portion 3^a and the nozzle 6 terminates at the end of the enlarged bore 2 where the tapered portion begins.

Threaded into the body 1 from one side, is a pipe 13 having the forward end 14 screw threaded to enter through the side thereof which pipe 12 leads from the fuel supply, not shown.

The pipe end 14 opens into a chamber 15 surrounding the conical end 6 of the nozzle 5.

By the construction shown and described, air is fed through the pipe 12 into the nozzle end 6, under pressure, but the pipe 13 does not contain any liquid or fluid under pressure, the flow of the liquid or fuel through the pipe 13 being caused by the suction created in the chamber 15 by the passage of the air under pressure from the pipe 12 through the nozzle end 6 to the bore 3 and into the sleeve 1.

In the structure shown in Fig. 3, the nozzle end 6 is replaced by a longer nozzle 6^a and the body 3 is replaced by a tapered body 3^a.

The tapered body 3^a is of considerable length and at the outer end has a reduced bore giving a less sturdy construction than the body 3 shown in Fig. 1.

The result is that the body 3^a will break down under excessive heat when used as a nozzle and consequently can not be employed on structures where the heat is excessive, so that on structures as shown in Fig. 3, their adaptation is limited to the more fragile forms of heaters, the more sturdy form being confined to the structures illustrated in Figs. 1 and 2. Moreover the nipple 6^a is provided with a wrench-receiving enlargement 10, and the pipe 12 is provided with a cut-off valve 17 by means of which a stream of air under pressure may be directed through the nipple 6^a to cause the feed of fuel through the pipe 13.

In Fig. 3 the two pipes 12 and 13 are joined together by bridge pieces 16 to serve as a handle for facilitating the handling of the burner shown in Fig. 3.

The structure of Fig. 3 constituting the small type of nozzle is essential and convenient and is designed for the purpose of cleaning automobiles and for other like uses about garages, for the engines and similar classes of machinery often become covered with grease and oil.

In most garages, there are air tanks with pipes running to various parts of the shop which can be connected to the part 12 by a hose.

The pipe 13 may represent a short hose to be dropped into a bucket of gasoline and the whole be moved from place to place, after which the valve 17 is opened so that

the air from the air tank is drawn in and atomizes and sprays the gasoline from the nozzle to produce an efficient cleaning stream of gasoline.

By reducing the bore of the nozzle tip 3^a, this might be used as a burning tip for burning off the spines from cactus for feeding cattle.

With respect to the burner shown in Fig. 1, the device may be employed with heavy fuel, with any suitable character of burner, in power plants, locomotives, etc.

In using the nozzle structure as an oil burner under a steam boiler, instead of air under pressure in the pipe 12, steam from the burner is used.

An auxiliary air tank may be used in connection with this device so that in starting a fire under a cold boiler, air under pressure may be fed into pipe 12 until there is sufficient steam in the boiler to operate said burner.

What is claimed is:—

A burner of the character described, comprising a main body portion having a pair of aligned axial bores formed therethrough, one of greater diameter than the other, a tapered portion between the said bores, the bore of greatest diameter being interiorly threaded, a minor body portion comprising a body of a diameter equal to the diameter of said main portion and having a relatively large bore therethrough and further having a reduced extension constituting an inner nozzle and adapted to thread into said threaded bore, said inner nozzle terminating at the end of the enlarged bore, said bore in said minor portion extending into said nozzle and said nozzle having an axial bore therethrough of materially less diameter than that bore in the minor portion, an air inlet nipple threaded at one end into the bore of the minor portion, an air pipe connected thereto, and a fuel inlet tube opening into the bore of greater diameter in the main body portion at a point slightly in the rear of the outlet of said nozzle and directed at an inclination toward the discharge end of the burner.

In testimony whereof, I affix my signature hereto.

ROBERT C. WADE.
